UNITED STATES PATENT OFFICE.

THEODORE ECK, OF BLUFFTON, INDIANA.

CHIMNEY-MORTARING MACHINE.

1,200,091.

Specification of Letters Patent.

Patented Oct. 3, 1916.

Application filed March 29, 1916. Serial No. 87,577.

To all whom it may concern:

Be it known that I, THEODORE ECK, a citizen of the United States, residing at Bluffton, in the county of Wells and State 5 of Indiana, have invented certain new and useful Improvements in Chimney-Mortaring Machines, of which the following is a specification.

This invention relates to an improved 10 chimney mortaring machine and the principal object of the invention is to provide a device so constructed that it may be used in connection with a chimney or smoke stack for facing the inner surface of the 15 chimney with mortar thus preventing the danger of fire caused by the mortar breaking out.

Another object of the invention is to so 20 construct this device that it may be lengthened according to the depth of the chimney.

Another object of the invention is to so 25 construct this device that applying brushes may be mounted for sliding beneath the mortar feeding housing.

Another object of the invention is to so 30 construct this device that it will be easily portable for movement from one place to another.

This invention is illustrated in the accompanying drawings, wherein:—

Figure 1 is a view showing the device in elevation and applied to a chimney shown in vertical section. Fig. 2 is an enlarged view in elevation of the opposite side of the 35 actuating mechanism mounted upon the top of the chimney. Fig. 3 is an enlarged sectional view taken on the line 3—3 of Fig. 1. Fig. 4 is an enlarged sectional view taken on the line 4—4 of Fig. 1. Fig. 5 40 is a perspective view of one of the brushes.

The driving disk 10 which is provided with a stub axle 11 is rotatably supported in the bearing 12 of the supporting frame 13 and is turned by means of a crank 45 handle 14 connected with the stub axle 11. A pitman 15 is pivotally connected with the driving disk 10 by means of a bolt 16 and carries a collar 17 which is pivotally connected with the pitman by means of the pin 18.

This collar 17 further carries a set screw 19 which passes through a threaded opening formed in the collar as shown in Fig. 4.

The mortar feeding means is connected 55 with the frame 13 by means of a bracket

or clamp 20 and includes pipe sections 21 which are releasably connected by suitable couplers 22. It will therefore be seen that this conduit can be lengthened by increasing the number of sections 21 or can be 60 shortened by removing one or more of the sections. A funnel or hopper 23 fits into the upper pipe section 21 thus making it easy to pour the mortar into the conduit. The lower pipe section is connected with 65 the distributing head which head is also tubular and includes side arms 24 and end arms 25. This rectangular head has its arms provided with perforations as shown at 26 which are positioned in the lower 70 portions of the arms so that the mortar can run freely out of these arms when the device is in use.

The brushes 27 and 28 are mounted upon the lower section 29 of the brush handle or 75 actuating rod and it will thus be seen that the mortar passing out through openings 26 will drop upon the bristles of the upper brush 27 and that any mortar which passes through the bristles of brush 27 without adhering to the inner face of the chimney 30 will be caught by the bristles of the lower brush 28 and applied to the chimney. These sections 29 of the brush handle are releasably connected by bolts or other fasteners 31 80 and the upper section passes through the guiding brackets 32 carried by the base of frame 13 and is then passed through the sleeve or collar 17 and held therein by means of the set screw 19. It will thus be 85 seen that by this construction the brushes may be releasably held at the desired distance beneath the distributing heads of the mortar feeding mechanism thus permitting the proper length of strokes for the brush 90 handles as the driving disk 10 rotates. This driving disk has been shown provided with a crank handle for rotating the disk but it is obvious that if desired any other suitable means could be employed for rotating the 95 disk.

When in use the apparatus is installed as shown in Fig. 1 and water is first poured into the feeding device. The chimney will first of course, have been cleaned to remove 100 the soot and as the device is operated, the water will be applied to the walls of the chimney thus doing away with the dry walls which ordinarily would prevent the mortar from properly sticking. After the 105 110

water has been applied to the chimney wall, the mortar is poured into the hopper 23 and will pass down the conduit into the distributing heads. The mortar will then pass 5 out through the opening 26 and will be applied to the chimney wall. This device may be operated either by first putting the distributing means and applying mechanism at the bottom of the chimney and applying 10 the mortar as the device is drawn outwardly or it may be operated in the reverse manner and the upper portion of the chimney coated first. When the wall of the chimney has been completely coated, the apparatus 15 can then be removed and conveyed to the next place where it is to be used.

I have therefore provided a mortar applying device which can be easily operated and which will be light and durable.

20 What is claimed is:—

1. A device of the character described comprising a coating apparatus comprising a supporting frame, driving mechanism carried by said frame and including a disk, a 25 pitman connected with said disk, feeding means including a conduit connected with said supporting frame and a distributing head at the lower end of said conduit, a brush positioned beneath said distributing 30 head, and a handle for said brush connected

with said pitman and receiving vertical movement as said disk rotates.

2. A coating machine comprising a supporting frame, actuating means carried by said supporting frame and including a rotatably mounted disk and a pitman pivotally connected with said disk to one side of the center thereof, feeding means suspended from said frame, applying means positioned beneath said feeding means and 40 having an elongated handle, and means connecting the handle of said applying means with said pitman for moving said applying means longitudinally in a chimney as said disk rotates. 45

3. A coating machine comprising a supporting frame, actuating means rotatably connected with said supporting means, applying means, a handle for said applying means, a link connecting said handle with 50 said rotatably mounted actuating means, and feeding means extending in operative relation to said applying means.

In testimony whereof I affix my signature in presence of two witnesses.

THEODORE ECK.
